BRUSH SPRING RETRCTOR

Herbert A. Krause, Brookfield, Ill., assignor to
General Motors Corporation, Detroit, Mich., a
corporation of Delaware

Application January 12, 1949, Serial No. 70,506

4 Claims. (Cl. 81—3)

1

This invention generally relates to hand tools and more particularly to a tool for retracting brush fingers of dynamoelectric machines.

The principal object of the invention is to provide a hand tool which may be readily engaged with brush fingers in the confined space they occupy within the frame of a dynamoelectric machine adjacent a commutator or the slip rings of such machines.

The various features of my brush finger retracting tool will become apparent by reference to the following detailed description and drawings of this tool.

Figure 1 of the drawings is an enlarged perspective view of a portion of the tool, shown in engagement with a brush finger of a brush holder of a dynamoelectric machine, with parts broken away.

Figure 2 is a vertical elevation of the tool.

Figure 3 is a sectional view taken on line 3—3 of Figure 2 with parts shown broken away and in section.

Figure 4 is an enlarged perspective view of a part of the tool engageable with the finger to be retracted.

Figure 5 is a plan view of the tool with parts broken away and in section.

Figure 6 is a vertical elevation of the tool with the parts shown broken away and in section and in different operative relation.

As best illustrated in Figure 2, the tool comprises an L shaped tool head, generally indicated at 1, and a lever, generally indicated at 3 and pivotally connected to the head. A handle 5 is secured to the outer end of the lever 3 and is shown extending along one side of the head and provided with a circular transverse inner end pivot portion 7 extending through a transverse hole 9 in the vertical arm 8 of the head adjacent the upper end for angular and axial movement therein. A lug 11 is secured to the outer end of the pivot portion 7 and extends along the other side of the head toward the outer handle end of the lever 3 as best illustrated in Figures 1, 3 and 5. The head is also provided with a hole 13 normal to and intersecting the transverse hole 9 and a helical compression spring 15 is positioned in the hole 13 between the bottom thereof and the pivot portion 7 of the lever 3, as best shown in Figure 3, to exert sufficient frictional force therebetween to prevent relative angular and axial movement of these parts. An abutment plate 17 is secured to the upper end of the vertical head arm 8 adjacent the transverse hole 13 and this plate extends beyond the sides and one end thereof and forms side and end abutments engageable by the lever 3 or the lug 11 thereon. It will be evident that, if the lever pivot portion 7 is manually moved axially sidewise in the direction of

2

the arrows shown in Figures 1, 3 and 5 to the full line position with respect to the head arm 8 against the frictional force exerted by the spring 15, the lug 11 on the outer end of the lever pivot portion 7 is positioned below the projecting end and one side portion of the head abutment plate 17 and subsequent clockwise movement of the lever 3 and handle 5 thereon with reference to the head 1, as shown by the arrows in Figures 1 and 2, causes the lug 11 to contact and move the head in the same direction. Conversely if the lever pivot portion 7 is moved axially in the opposite direction with respect to the head to the dotted line position, Figure 5, the lug 11 is positioned beyond the projecting end and other side portion of the head abutment plate 17 and subsequent clockwise movement of the lever and handle thereon causes the lever to contact the abutment plate and move the head in the same direction.

The other horizontal leg 19 of the head 1 extends longitudinally inwardly toward the lever handle 5 below the transverse hole 9 in the vertical leg 8 through which the lever pivot portion 7 extends. A U shaped bracket 20 having upstanding legs 21—23 embracing and secured at the upper ends to each side of the outer end portion of the horizontal head arm 19 to position the bottom portion 25 of the bracket vertically downwardly from the arm, to form an open ended socket portion 27 between the arm 19 of the head and the legs 21—23 and bottom 25 of the U shaped bracket 20 secured thereto. The bottom 25 of the bracket is provided with an upturned abutment or lip 29 adjacent the outer end of the socket 27 as best seen in Figure 6.

Depending upon the limited space available adjacent the brush finger of the dynamoelectric machine to be retracted by this tool the lever 3 is positioned transversely and angularly relative to the tool head 1 in which position it is normally held frictionally by the helical spring 15 for engagement of the lever 1 or lug 11 thereon with the abutment plate 17 so that the socket portion 27 in the outer end of the horizontal arm 19 of the tool head 1 may be readily engaged with the outer end surface of a brush finger 31 by manipulation of the lever handle 5, as best shown in Figure 1, with the horizontal arm 19 of the tool head 1 above and parallel to the upper end surface of the finger. The brush finger 31, shown in Figure 1, is a radial end portion of a spiral brush spring 32, the other end of which is secured by a pin 33 to a brush holder 35 provided with a brush slot 37 adjacent the outer end of the finger. The finger 31 has a pad 39 secured to the lower face adjacent the outer end and normally urged by the spring portion 32 toward the outer end of the brush slot to

urge the finger pad 39 into contact with the outer end of a brush 40 in the slot 37 in order to retain the inner end of the brush in contact with the outer surface of a dynamoelectric machine armature or slip ring, not shown, in conventional manner. The outer end of the finger 31 is shown in Figures 1 and 2 extending into the socket 27 between the horizontal head arm 19 and the U shaped bracket 20 with the outer end of the finger pad 39 in engagement with the inner end surface of the bracket lip 29, to limit further movement of the head arm on to the finger.

With the finger 31 located in the socket 27 of the tool head 1 in the above described manner and the head abutment plate 17 engageable by the lug 11 on the lever 3, as shown in Figures 1 and 3, or with the lever 11 engaged with the head abutment, as shown in dotted lines in Figures 1 and 5, if sufficient space is available adjacent the tool handle 5 it may be moved outwardly clockwise with reference to the finger 31 as shown by the arrows in Figures 1 and 2 to transmit clockwise retracting movement to the finger 31 to uncover the outer end of the brush holder slot 37 in order that the other hand of the tool operator may readily and safely insert and remove the brush 40 from the brush-holder slot 37.

If there is not sufficient space available to move the handle 5 outwardly clockwise an amount necessary to fully retract the finger the handle 5 and lever 3 may be moved counterclockwise or inwardly with reference to the head 1 and finger 31 to a position below and at an angle to the brush finger 31 so that an angularly upward endwise thrust may be exerted on the handle 5 and lever 1 to cause retraction of the finger 31. The relative position of the lever 3 relative to the head 1 and finger 31 when so retracted is shown in dotted lines in Figure 2 and the direction of thrust on the lever being indicated by the dotted arrow. If there is not sufficient clearance to rotate the handle 5 relative to the head 1 from the full line position shown in Figure 2 an endwise thrust on the lever 3 in the direction of the arrow will likewise cause clockwise retracting movement of the tool head 1 and brush finger 31 as the lever 3 is pivoted to the vertical arm 8 of the head in vertically offset relation with respect to the point of engagement of brush finger 31 by the horizontal arm 19 of the tool head.

In order to engage certain otherwise inaccessible brush fingers 31 the complete retracting tool may be inverted and the head 1 rotated approximately a half revolution with respect to the lever 3 to the position shown in full lines in Figure 6 to also enter the outer end of the brush finger into the socket portion 27 of the tool head so that the outer end of the finger pad 39 is contacted by the outer end surface of the lip or abutment 29 to retract the finger by either an angular movement of or by the application of an endwise force on the lever handle 5 in the previously described manner.

This brush finger retracting tool enables safe removal and replacement of brushes in brush-holders located in various and otherwise inaccessible positions within dynamoelectric machines.

I claim:

1. In a retracting tool for an angularly retractable brush finger, a tool head having means in one end engageable with one end of the brush finger, an elongated lever having a transverse pivot mounted on the opposite end of said head

for lateral and angular movement with respect to an axis located in vertical offset relation to said finger engaging means of said head, said head having abutments thereon spaced laterally apart, said lever also having surfaces spaced laterally apart, each lever surface contacting one of said head abutments upon lateral and angular movement of said lever thereby causing angular movement of said head and angular retracting movement of the brush finger, said lever being also movable endwise of the lever pivot and the offset brush finger engaging means of said head when engaged with a brush finger to cause relative angular movement of said head and corresponding angular retracting movement of the finger.

2. In a retracting tool for an angularly retractable brush finger, a tool head having angularly offset legs, one leg having brush finger engaging means, a lever mounted at one end for lateral and angular movement in the other leg of the head, frictional means engaging said head and lever to restrain relative lateral and angular motion between said head and said lever, said head having laterally spaced abutments, and said lever having a pair of abutments spaced laterally apart a greater distance each engageable with a head abutment upon lateral and angular movement of said lever to transmit angular movement to said head to angularly retract the brush finger engaged thereby, the offset mounting of said lever and said finger engaging means on said head also causing relative angular movement of said head relative to the lever to retract the brush finger when the lever is moved endwise toward the end of the brush finger engaged by said head.

3. A tool for retracting brush fingers on dynamoelectric machines comprising a lever having a lateral arm rigidly attached thereto and an L-shaped head having a base portion and a leg portion and fastened to said arm for pivotal and extended axial movement with respect thereto, the base portion of the L-shaped head containing said lateral arm and its axis, said axis being perpendicular to the leg portion of said L-shaped head, and the unattached end of the leg of said L-shaped head being provided with brush finger engaging means, whereby when axial movement is given to said lever, said head and a brush finger which said means is adapted to engage are angularly displaced.

4. A tool for retracting brush fingers on dynamoelectric machines comprising a lever having a lateral arm rigidly attached thereto, a head provided with an abutment and fastened to said arm for pivotal and extended axial movement with respect thereto, means rigidly attached to said arm adapted to engage said abutment and prevent pivotal movement of said head with respect to said arm in one rotative direction only, and brush finger engaging means on said head, whereby leverage and axial movement may be applied to said lever to angularly displace said head and brush finger.
